UNITED STATES PATENT OFFICE.

CHARLES DEITSCH AND EDWARD J. DEITSCH, OF NEW YORK, N. Y.

DESIGN FOR A BELT.

SPECIFICATION forming part of Design No. 30,921, dated May 30, 1899.

Application filed January 18, 1899. Serial No. 702,594. Term of patent 3½ years.

To all whom it may concern:

Be it known that we, CHARLES DEITSCH and EDWARD J. DEITSCH, residing in the city of New York, borough of Manhattan, county and State of New York, have invented and produced a new and original shape or configuration, a Design for a Belt, of which the following is a specification, reference being had to the accompanying drawings, forming a part thereof, of which—

Figure 1 is a view in elevation of the outer surface of the belt, and Fig. 2 is a view in elevation showing the inner surface of the belt to be placed in contact with the body of the wearer.

The letters of reference designate like parts in both of said figures.

The letter X represents the body of the belt, which may be made of leather and having loose stiches or loops A extending around the entire outer edge of the belt, and these loose stiches or loops may also be made of leather.

B represents a sliding keeper which may also be made of leather and provided with loose stiches or loops extending around the entire outer edge thereof.

C is a loose loop fastened to the buckle end of the belt, through which the keeper B may be moved upon the belt.

D is a tongue or flap secured to the belt upon the inner wearing-surface thereof and having holes into which the tongue of the buckle may be inserted.

The features of our design consist of a belt 35 provided with loose stiches or loops extending around the edge or border of the belt the entire length thereof and the sliding keeper upon the belt, also having loose stiches or loops extending around the entire outer edge 40 or border thereof.

Having described our invention, what we claim as new, and desire to secure by Letters Patent, is—

The design for a belt as herein shown and 45 described.

In testimony whereof we have hereunto affixed our signatures in presence of two witnesses.

CHARLES DEITSCH.
EDWARD J. DEITSCH.
